RIGID TENSION-TRUSS BRIDGE

John W. Beretta, San Antonio, Tex.

Application December 9, 1946, Serial No. 715,119

3 Claims. (Cl. 14—18)

(Granted under Title 35, U. S. Code (1952),
sec. 266)

1

The invention described herein may be manufactured and used by or for the Government for governmental purposes, without payment to me of any royalty thereon.

This invention relates to trusses and more particularly to bridge trusses.

An object of this invention is to provide a truss bridge having the necessary qualities of stability, rigidity and carrying capacity, both vertically and laterally, in which the main structural members, other than the end members, are capable of taking tension only. The utilization of members capable of taking tension only, such as cables and rods, makes it possible to break down the component parts of the bridge into relatively small and light units which can be transported to comparatively inaccessible spots over poor roads such as are found, for example, in the mountains, and there assembled into a long-span, high-capacity bridge. This type of construction is also highly advantageous in more approachable construction areas where access is had to the bridge site over relatively good roads, in that it makes possible a much lighter bridge structure than the comparable conventional suspension bridge because of the elimination of the usual stiffening trusses or girders for distributing the concentrated live loads passing over the bridge in such manner that those loads are applied to the main cables over a considerable portion of their length in order not to change materially the normal parabolic curve of the main cables.

In the illustrated embodiment of the invention, the top and bottom chords are prestressed in tension to an amount such that the tensional stresses are never reversed by compressive stresses set up by live loads on any portion of the bridge or even by the combined dead loads and live loads due to wind, impact and temperature stresses. The top and bottom chords are connected by members which are also capable of taking tensional stresses only, these members being arranged to form, in conjunction with the top and bottom chords, a series of triangles.

The procedure, therefore, in design, will be assumptions of dead and live load conditions and determination of preliminary stresses and sections. On the basis of these determinations, static analysis under dead load and elastic analysis under live load can be made. Stresses and sections then can be corrected, and on the basis of this correction, the stressing of the top and bottom chord members can be determined, taking into account the elastic deformation of the members under the various conditions of loading to produce maximum stresses. Upon determining these maximum stresses and elastic deformations,

2

the amounts of prestressing necessary to prevent reversal of stress can be computed.

Another object of the invention is to provide a truss bridge including a floor consisting of transverse structural members, longitudinal structure members and means for fixedly connecting certain ends of the longitudinal structural members to the transverse structural members and hingedly connecting certain of the other ends with the transverse members, whereby the longitudinal structural members may be articulated on the transverse members, thus providing a series of nodes in each panel which dampen out any tendency for the bridge to have vibrations of wide amplitude in a vertical plane, over a large portion of its length.

Another object of the invention is to provide a multi-span truss bridge composed of trusses having top chords, bottom chords and web members all being capable of taking tension only.

In a conventional suspension bridge there are three essential main elements which are the cables, towers and anchorages and various auxiliary members comprising suspenders, floor-beams, stringers, and lateral system. There are, also, the stiffening trusses or girders for distributing the concentrated live loads in such manner that these live loads are applied to the main cables by all suspenders in substantially equal amounts, so that the normal parabolic curve of the main cables will not be changed materially under live load. The stiffening truss carries no dead load as it is supported from the main cables. Furthermore, it carries only substantially twenty per cent of the live load; the balance, approximately eighty per cent of the live load, is actually carried by the main cables. The stiffening truss on the conventional suspension bridge is therefore a very uneconomic member considering the work it actually performs, as, for example, for two-lane suspension bridges of military design, ranging in lengths from one hundred and fifty feet to six hundred feet, of fifty ton capacity, the stiffening truss weighs approximately fifty per cent of the total structural steel work in the bridges exclusive of main towers. The top chords, bottom chords and the diagonal members of the stiffening truss must be designed to take either tension or compression, and the permissible tension stress must be reduced to provide for the proper slenderness ratio of the compression unit stress formula. In the stiffening truss while one chord member is taking compression stresses the other chord will take tension stresses and the bottom chords act also as the wind chord of the horizontal wind truss. In this capacity it takes either tension or compression and its size must be in-

creased to provide for these additional stresses. The lateral members are generally made of ordinary structural steel. In the main cables of all suspension bridges, and in inverted or storm cables where they are utilized, the horizontal components of the stresses in such members are equal throughout their lengths. Therefore, it can be seen that if conventional stiffening trusses on suspension bridges could be dispensed with by suitable means that would simultaneously guarantee a level roadway without objectionable wave action under loads and without distortion of the parabolic curve of the cable, a saving, particularly in weight, could be had.

It is, therefore, another aim and purpose of this invention to provide a rigid tension-truss bridge in which the conventional stiffening truss is eliminated thereby making possible a large saving in the material required for the construction of the bridge.

With the above and other objects and advantages in view the invention consists of certain features of construction and operation of parts which hereinafter will be described and shown in the accompanying drawings, in which:

Fig. 1 is a diagrammatic side view of a truss bridge embodying the novel web system of the instant invention;

Fig. 2 is a diagrammatic top plan view thereof;

Fig. 3 is a diagrammatic side view of the truss bridge illustrated in Figs. 1 and 2 showing a different arrangement of certain of the diagonal members of the trusses;

Fig. 4 is an enlarged fragmentary detail view showing the manner of connecting the stringers to an end tower column and floor beam and also the manner of connecting a bottom chord to the end tower column;

Fig. 5 is a fragmentary, vertical sectional detail view taken on line V—V of Fig. 4;

Fig. 6 is a fragmentary detail view showing the manner of connecting the vertical and diagonal tension members to the floor system of the bridge;

Fig. 7 is a plan view of the floor system, with parts broken away and in section;

Fig. 8 is a fragmentary sectional view thereof taken on line VIII—VIII of Fig. 7;

Fig. 9 is a diagrammatic view of another modified form of truss bridge embodying three spans;

Fig. 10 is a diagrammatic top view thereof; and

Fig. 11 is a diagrammatic view showing a modified arrangement of the diagonal members of the trusses in Fig. 10.

Referring more specifically to the drawings, there is diagrammatically illustrated in Figs. 1 and 2 one form of the improved rigid tension-truss bridge constructed in accordance with my invention which includes spaced pairs of end tower columns 10 mounted on piers 11, with the trusses indicated generally by A connected to and extending between the towers. The truss A is composed entirely of tension members of steel wire ropes, cables or the like, including upper and lower chords prestressed in tension. The other structural or supporting units, such as the flooring of the bridge, may be composed of structural units capable of taking tension, compression, flexure, or a combination of such stresses.

The tension members in the truss are arranged in a series of triangles and include top tension chords or cables 11, bottom tension chords or cables 12, diagonal intersecting flexible members 13 and vertical flexible members 14. The top

chords 11 are passed over the towers 10 and extensions thereof are anchored in abutments 16 in a conventional manner. Tension is applied to the top chords 11 by turnbuckles 18, which are similar to turnbuckles 18, or other functionally similar tensioning means which are preferably connected to the extensions 15. The amount of tension applied to the top chords is such that it is greater than any compressive stresses which may be transmitted by the members 13, 14.

The bottom tension chords 12 extend along the outer side of the outside lines of stringers or longitudinal members 17 of the floor system, more particularly indicated in Fig. 7, and are connected at their ends to the bottom of the towers 10 through turnbuckles 18 and shackles 19 engaging pins 20 on brackets 21 mounted on the tower cross-beams 10', so that the tension stress to which the bottom chords 12 are subjected is transmitted as an axial compression load to the lines of stringers 17 and 17'. Instead of connecting the ends of the bottom chords 12 to the tower cross-beams 10' they may be connected to the end stringers of the outside line of stringers 17 and the bottom chords may be connected to the transverse floor beams 22 by clamps 23 or the like.

The diagonal and vertical flexible members 13 and 14 respectively, are connected at their ends at spaced points 24 on the upper tension chords 11 and are connected at their lower ends to plates 25 connected to brackets 26 mounted on the ends of the floor beams 22 as more particularly illustrated in Figs. 4, and 6 to 8, inclusive. The diagonal members 13 serve to distribute any local loads to several points 24 along the top chords 11 instead of having these local loads taken to the top chords by the vertical members 14.

At the panel points 27, one end of each of the stringers 17 and 17' of the floor system is attached at 28 to the transverse floor beams 22 by a rigid connection, while one end of each of the other ends of the stringers are hingedly connected to the floor beams by pins 29, so that the local deflections at any panel point are taken care of by the hinge connection. The hinge pins 29 are located below the neutral axis of the stringers 17 and 17' so that compression in the stringers produces an upward bending of the entire floor system. This construction takes care of the panel point deflections under the passage of loads and provides articulation in each panel, with the articulation providing a series of nodes in each panel and damping out any tendency for the bridge to have vibrations of wide amplitude in a vertical plane over a large portion of its length.

In order to provide for the requisite rigidity to withstand horizontal wind and other lateral forces, the floor system is provided with lateral bracing 30 and horizontal wind cables 31 made of steel wire ropes or strands, Figs. 2 and 7.

A slightly different arrangement of the diagonal members is shown in Fig. 3 from that shown in Fig. 1. In this arrangement certain diagonal members 32 extend over more than one panel near the towers 10 in order to secure the requisite rigidity to transport vehicles and the like satisfactorily, with the diagonal members 13' in the middle of the bridge remaining the same as in Figs. 1 and 2. Other arrangements of the diagonal members would also provide the same results.

Bridges embodying this invention may take other forms than that disclosed in Figs. 1 to 3.

inclusive, which show trusses in parallel over a single span. In Figs. 9 and 10 there is shown a three span bridge consisting of a center span indicated generally by M having top and bottom chords 33 and 34, respectively, connected to and between main tower columns 35, a web system including diagonal flexible members 36 and vertical flexible members 37 and end spans indicated generally by S. Each of the end spans S includes top and bottom chords 38 and 39, respectively, connected to and extending between the tower columns 35 and end columns 40, a web system including diagonal flexible members 41 and vertical flexible members 42, with anchored backstays 43 for stressing the main span top chords 33 and span top chords 38 in tension to such an amount that this tension is never entirely neutralized by the compression stresses transmitted to it by members 36, 41 as a result of live load, impact, wind and temperature stresses. The top and bottom chords may be continuous in all the spans, whereas the web system may be separate for each span. In order to provide for the requisite rigidity to withstand horizontal wind and other lateral forces, the floor system is provided with a center span, diagonal bracing 44, end span diagonal bracing 45, center and end span wind cables 46 and 47, respectively, center span transverse floor beams 48, and end span transverse floor beams 49.

In Fig. 11 a slightly different arrangement of the diagonal members is disclosed from that disclosed in Fig. 9. In this arrangement certain diagonal members 50 of the center span M', extend over more than one panel near the tower columns 35' both in the center span M' and end span S' in order to secure the requisite rigidity to transport vehicles and the like satisfactorily, with certain of the diagonal members 36' and other structural units remaining the same as in Fig. 9.

It will thus be seen that there has herein been provided a new, novel and efficient form of truss bridge having a similarity in appearance to suspension bridges, but which acts as a true truss throughout its length and under normal loads. The main chords act as the top chords and the inverted curve bottom chords become the bottom chords and under abnormal loads such as aerodynamic uplift the action reverses with the vertical and diagonal members of the bridge being designed to take tension stresses only; merely going in and out of action under various combinations of loading with one diagonal acting in any one panel at a time.

Even though the basic principle of the instant invention is to provide a more economic structure for truss bridges over rivers and the like and having certain features of construction and operation of parts, it is nevertheless to be understood that the structure may be used for other purposes such as long span trusses in buildings and that various changes may be made therein, if the changes do not depart from the spirit or scope of the claims.

Having thus described my invention, what I claim as new and wish to secure by Letters Patent is:

1. A truss bridge comprising tensioned upper cables anchored at the ends and supported intermediate their anchored ends on spaced towers to form an upper chord, a cross-beam mounted on each tower below the upper cables, an articulated floor system extending between said tower cross-beams, said floor system being attached to said

70 75

tower cross-beams and including a plurality of pivotally connected sections, flexible vertical suspenders secured to the floor system at the points of pivotal connection therein and to the upper chord at spaced points, tensioned lower cables secured at their ends to said tower cross-beams and intermediate their ends to the floor system at the points of pivotal connection therein to pre-stress said floor system in compression, and flexible diagonal members connected between said spaced points and said points of pivotal connection to form a truss structure.

2. A truss bridge comprising parallel tensioned upper cables anchored at their ends and supported intermediate their anchored ends on spaced towers to form an upper chord, flexible suspenders secured to each upper cable at corresponding opposite spaced points and depending vertically therefrom, said towers each including a transverse tower cross-beam, a floor system attached to and extending between the tower cross-beams and including a plurality of interconnected longitudinal stringers and spaced transverse beams, said spaced beams being connected to said suspenders to determine panel points, tensioned lower cables connected at their ends to the tower cross-beams and supported intermediate their ends by said spaced beams to pre-stress said stringers in compression, and intersecting flexible diagonal members connected between said panel points and the spaced points on said upper cables to complete a truss structure.

3. A truss bridge comprising parallel tensioned upper cables anchored at their ends and supported intermediate their ends on spaced towers to form an upper chord, flexible suspenders secured to each upper cable at corresponding opposite spaced points and depending vertically therefrom, said towers each including a pair of spaced vertical tower columns and a transverse tower cross-beam interconnecting the columns of each tower, a floor system attached to and extending between the tower cross-beams and including a plurality of floor panel sections, said floor panel sections each including parallel stringers and a transverse floor beam rigidly connected at one end of said parallel stringers, the opposite ends of said stringers being pivotally connected to the transverse floor beam of the adjacent panel, said transverse floor beams being connected to said suspenders, tensioned lower cables connected at their ends to the tower cross-beams and supported intermediate their ends by said transverse floor beams to pre-stress said stringers in compression, and intersecting flexible diagonal members connected between said transverse floor beams and the said opposite spaced points on the upper cables to complete a truss structure.

JOHN W. BERETTA.
